UNITED STATES PATENT OFFICE.

WILLIAM L. FINNE, OF ELIZABETH, NEW JERSEY.

SAFETY APPLIANCE FOR ELEVATORS.

1,244,723.

Specification of Letters Patent. Patented Oct. 30, 1917.

Application filed June 12, 1917. Serial No. 174,382.

To all whom it may concern:

Be it known that I, WILLIAM L. FINNE, a citizen of the United States, residing at Elizabeth, in the county of Union and State of New Jersey, have invented certain new and useful Improvements in Safety Appliances for Elevators, of which the following is a full, clear, and exact specification.

This invention relates to safety means for preventing persons from becoming hurt by being accidentally caught between the floor of the elevator car and the top of the door leading to the shaft, or between the top of the car and the landing.

It is the aim of the invention to provide improved means for automatically breaking the circuit to the motor and controller of an electrically operated elevator, and also applying the brake, whenever any obstruction is placed between the floor of the car and top of the door leading to the shaft or between the top of the entrance to the car and the landing. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a diagrammatic view of a portion of an elevator shaft with a plurality of doors leading thereto, a car, and electric controlling mechanism for the same, said mechanism being illustrated in normal position as when the circuit to the motor and controller is closed and the brake is not applied, and

Fig. 2 is a detail of one end of one of the safety bars, showing on a larger scale the means for supporting it and the switch or circuit breaker which it controls.

Fig. 3 is a section on the line III—III of Fig. 2.

It will be understood that the elevator shaft 1 may be of any length and be provided with any desired number of entrance doors 2 from different floors. The car 3 is equipped with the usual controller 4 from which one wire 5 runs to one of a pair of circuit breakers 6 mounted adjacent to each of the openings or doors 2 leading to the

shaft. Wires 14 run from the main switch 12 to a switch board 15, and from said switch board wires 16 run to the motor 17 which operates the car 3 by means of a cable indicated in broken lines at 23 as passing over a sheave 24 and connected at 25 to the top of the car.

From the controller 4 another wire 22 leads to the switch board 15, where it may be placed in circuit with one of the wires 14 running to the main switch 12. Another wire 21 leads from the controller 4 to one of a pair of circuit breakers 19 mounted at opposite sides of the entrance to the car 3. From one of the main feed wires 13, the wire 11 runs direct to the magnet 10, energizing same on being connected up with the wire 9, which runs in series with the circuit breakers 6 on each side of the landing doors and continues in series through the wires 7, 8 and 5, through the controller 4 without interruption, thence through the wire 21 connected in series with the circuit breakers 19, through the wires 20, and back to another one of the main feed wires 13 through the wire 18, making a complete circuit which will only be interrupted when an accident happens causing movement of any one of the circuit breakers 6 or 19 from its normal closed position. Such movement of any one of the circuit breakers 6 or 19 will interrupt the circuit to the motor and controller through demagnetization of the magnet 10 and consequent opening of the switch 12, whereupon the armature 41 thereof will be released and in moving downward will swing the lever 43 so as to open the main switch through the connection 45 between said switch and the lever 43, and tighten the brake band 46 thus stopping the car.

Each circuit breaker 6 and 19 comprises two spaced contact plates 38 and 39 suitably mounted in a protecting casing or box 40, as best shown in Fig. 2. These contact plates are normally bridged by a V-shaped member 37 carried at each end of a bar 26, one of which is arranged across the entrance to the elevator car near its top, and across the entrance or door leading to the shaft on each landing also near the top of said entrance or door. Each of these bars has downwardly bent end portions 27 clamped in brackets 28 which are mounted to slide vertically on a rod 30 extending between brackets 32 suitably fastened to the shaft or car as the case may be by bolts 33. A coiled

spring 34 is mounted around the rod 30 above the upper one of the brackets 28 for yieldingly holding the bar 26 down with the V-shaped member in position to bridge the contact plates 38 and 39. Below the lower bracket 28, a bumper spring 35 is coiled about the rod 30. The end of the bar 26 is fitted with a plug of insulating material 36 in which the V-shaped member is fastened so as to insure the insulation of the said bar 26.

From the foregoing it will be understood that if a person or other obstruction should become caught between the floor of the elevator car and the top of any one of the entrances or doors 2 to the elevator shaft when the car is moving upward, the safety cross bar 26 will be raised, its vertically bent end portions sliding upward on the rods 30 against the action of the springs 34, and the bridging members 37 separated from the contact plates 38 and 39, thereby interrupting the circuit to the magnet 10, and instantly stopping the car by applying the brake as already described. The operation will be the same should an obstruction be presented between the top of the entrance to the elevator car and the floor of a landing when the car is moving downward.

Having thus described my invention, what I claim as new and desire to secure by Letters Patent of the United States is:

1. The combination with an elevator shaft

having a door opening, of an elevator car to move in said shaft, a circuit for controlling said car, a vertically movable bar arranged across the entrance to said car and having vertically turned ends, brackets secured to said ends, vertical rods fastened to the car and on which said brackets are mounted to slide, a circuit breaker comprising two spaced contact plates in said car-controlling circuit, a bridging element carried by the end of the bar, and a spring coiled about one of the vertical rods for yieldingly holding said bridging element in contact with said contact plates.

2. The combination with an elevator shaft having a door opening, of an elevator car to move in said shaft, a circuit for controlling said car, a vertically movable bar arranged across the entrance to the car and having vertically bent ends, brackets secured to said ends, vertical rods fastened to the car and on which said brackets are mounted to slide, a circuit breaker comprising two spaced contact plates in said car-controlling circuit, a bridging member carried by one end of the bar, means for yieldingly holding said bridging member in contact with said contact plates, and a bumper spring coiled around said rod below said brackets.

In testimony whereof I have signed my name to this specification.

WILLIAM L. FINNE.
